UNITED STATES PATENT OFFICE.

HENRY C. EGERTON, OF RIDGEWOOD, NEW JERSEY.

DIAPHRAGM FOR DICTAPHONES, ETC.

Application filed May 9, 1919. Serial No. 296,016.

To all whom it may concern:

Be it known that I, HENRY C. EGERTON, a citizen of the United States, and resident of Ridgewood, county of Bergen, State of New Jersey, have made a certain new and useful Invention Relating to Diaphragms for Dictaphones, Etc., of which the following is a specification, taken in connection with the accompanying drawing.

10 This invention relates especially to diaphragms having attached or incorporated styli suitable for use in connection with dictaphones or similar devices. The diaphragms may be advantageously made of one or more layers of fabric carrying incorporated cured phenolic condensation cementing material, such as bakelite, condensite, or redmanol varnish compositions. The central portions of the diaphragms may 20 be advantageously stiffened by being given a projecting and more or less coned up contour, the relatively flat edge portions of the diaphragm inside the clamping members used giving relatively great flexibility so as 25 to allow the desired vibration of the central portions of the diaphragm to which one or more styli may in some cases be permanently connected during the molding and curing of the impregnated diaphragm 30 fabric, if desired. Sapphire or other cutting or recording styli may also be conveniently secured to such a coned up or otherwise stiffened diaphragm center by inserting them through an accurately positioned hole in the diaphragm and cementing the inner end of the stylus to the inside or outside of the diaphragm in connection 35 with suitable cementing material. Muslin or other woven fabric or cotton batting, etc., may be advantageously used when coated or impregnated with dried phenolic condensation cementing material for molding such diaphragms when the centers or other vibrating portions are of coned up or 40 projecting form to secure the desired stiffness, although where the stiffness is secured by additional thickness or layers of the treated fibrous material paper or other fibre may be used in whole or in part in 45 connection with the phenolic condensation cementing and stiffening material and the one or more styli may be adhesively secured to the stiffened vibrating portion of the diaphragm in such cases.

50 The accompanying drawings show in a somewhat diagrammatic way various illus-

trative embodiments of this invention, and Fig. 1 is a side view of a diaphragm for this purpose.

Fig. 2 is an enlarged side sectional view thereof; and

Fig. 3 is a side view partly in section showing a different construction.

The diaphragm may as indicated in Fig. 1 comprise a relatively stiffened coned up central portion 2 to which the stylus 3 may be cemented or otherwise rigidly secured and a relatively flat yieldable edge portion 1 may be formed on the diaphragm to facilitate its normal vibration under working conditions. Such a diaphragm may be conveniently formed of one or more layers of cotton cloth, cotton batting, or other suitable fabric carrying and preferably quite thoroughly impregnated with phenolic condensation cementing material, such as bakelite or condensite varnish compositions which may be present to the extent of forty to sixty per cent more or less in the dried impregnated fabric. Such impregnated fabric may when heated and softened be molded under pressure in a suitably shaped mold so that the heated and softened fabric may be forced into the desired contour and cured under pressure at such temperatures as 300° to 320° Fahrenheit, more or less for fifteen to thirty minutes or so as to preferably substantially completely cure the phenolic condensation cementing material and greatly strengthen and stiffen the cotton or other fibrous material with which it is incorporated. By forming such a diaphragm of several thicknesses of thin muslin preferably having loosely twisted threads the diaphragm wall may have a thickness of six to eight thousandths of an inch more or less when two ounce fabric is used and of course a greater number of layers of fabric or other fibrous material may be employed where each layer is thinner, or a relatively less number of layers of thicker material may be employed in some cases, and the wall thickness of the diaphragm may of course vary considerably according to the particular service desired.

The stylus, such as 3, of sapphire, glass, hard metal or other suitable material may be originally molded in the diaphragm, and secured thereto by the phenolic condensation cementing material, or in some cases the diaphragm may be originally formed in molds having such contour as to have a re-

55

enforced stylus seat or securing portion, if desired, containing relatively greater proportions of the cementing and stiffening material in some cases, and by forming a cavity within the point of the male mold the high molding pressure tends to force some of the softened or melted phenolic condensation cementing material into such a cavity to form some such reenforcement or lump 5 as 6 shown in Fig. 2 which greatly stiffens and strengthens the material. After the diaphragm is molded the hole 7 for the stylus may be bored, punched or otherwise formed in suitable jigs or locating devices 10 and then the stylus 3 which may have a cutting point or end 4 in some cases may be accurately positioned in the diaphragm by suitable jigs or spacing devices and cemented in place therein by any suitable cement 15 envelope 20 gaging the inner end 5 of the stylus. In some cases where no special reenforcing cementing material is originally used a suitable quantity such as 6 of any desired cementing material, such, for instance, as ambrroid or pyroxylin cement or the like may be used for this purpose and allowed to harden while the stylus is in the jig or setting device to ensure its accurate position 25 within the diaphragm. 30 In some cases diaphragms having duplex or multiple styli may be conveniently formed in this way and as shown in Fig. 3 such a diaphragm may have a coned up or stiffened central portion 9 gradually 35 merging into the relatively flexible edge portion 8 of the diaphragm and may have several styli 10, 11 secured to and projecting from the central portion of the stiffened diaphragm center which may be further stiffened and reenforced by the cementing material, such as 12, which may be used 40 to hold these styli in position and simultaneously stiffen the diaphragm center at this point. Of course substantially uniform 45 quantities of such cementing material should be used so as to ensure uniform pitch and stiffness of the diaphragm and for this purpose the cloth or other fibrous material used for forming such diaphragm should 50 be of substantially uniform weight and character and should contain substantially uniform quantities of the coating or impregnating phenolic condensation cementing material so that the weight, stiffness and 55 strength of the resulting diaphragms will be substantially uniform.

This invention has been disclosed in connection with a number of illustrative embodiments, forms, proportions, elements, parts, shapes, materials, compositions, conditions, and methods of preparation, production and use, to the details of which disclosure the invention is not of course to be limited, since what is claimed as new and what is desired to be secured by Letters

Patent is set forth in the appended claims:

1. The diaphragm for dictaphone and similar acoustic instruments formed of fabric carrying cured phenolic condensation cementing material, said diaphragm having a relatively flat flexible edge portion and a coned up projecting stiffened vibrating portion and a plurality of styli projecting through the wall of said diaphragm adjacent and adhesively secured to said projecting portion of the diaphragm. 70

2. The diaphragm for acoustic instruments formed of fibrous material carrying cured phenolic condensation cementing material, said diaphragm having a relatively flat flexible edge portion and a projecting stiffened vibrating portion and a plurality of styli adhesively secured to said projecting portion of the diaphragm. 80

3. The diaphragm for acoustic instruments formed of fibrous material carrying cured phenolic condensation cementing material, said diaphragm having a relatively flexible edge portion and a stiffened vibrating portion and a plurality of styli adhesively secured to said vibrating portion of the diaphragm and projecting therefrom at different angles. 85

4. The diaphragm for dictaphone and similar acoustic instruments formed of fabric carrying cured phenolic condensation cementing material, said diaphragm having a relatively flat flexible edge portion gradually merging into a coned up stiffened central projecting vibrating portion and a cutting stylus projecting through and adhesively secured to the wall of said diaphragm adjacent and substantially tangent to the tip of said projecting portion of the diaphragm by stiffening cementing material within the projecting portion of the diaphragm. 95

5. The diaphragm for dictaphone and similar acoustic instruments formed of fabric carrying cured phenolic condensation cementing material, said diaphragm having a relatively flexible edge portion gradually merging into a coned up stiffened central projecting vibrating portion and a cutting stylus projecting through and adhesively secured to the wall of said diaphragm adjacent the tip of said projecting portion of the diaphragm. 100

6. The diaphragm for acoustic instruments formed of fabric carrying cured phenolic condensation cementing material, said diaphragm having a relatively flexible edge portion and a stiffened vibrating portion and a stylus adhesively secured to the wall of said diaphragm and projecting through said vibrating portion of the diaphragm. 110

7. The diaphragm for dictaphone and similar acoustic instruments formed of fibrous material carrying cured phenolic condensation cementing and stiffening material, 125

said diaphragm having a relatively flat flexible edge portion and a substantially conical projecting stiffened central portion and a stylus projecting through the wall of said diaphragm adjacent and substantially tangent to the tip of said projecting portion and adhesively secured in position by cementing material within said projecting portion of the diaphragm.

10 8. The diaphragm for dictaphone and similar acoustic instruments formed of fibrous material carrying cured phenolic condensation cementing and stiffening material, said diaphragm having a relatively flexible edge portion and a substantially projecting stiffened central portion and a stylus projecting through the wall of said diaphragm adjacent to the tip of said projecting portion and adhesively secured in position by cementing material within said projecting portion of the diaphragm.

15 9. The diaphragm for dictaphone and similar acoustic instruments formed of fibrous material carrying cured phenolic condensation cementing and stiffening material,

said diaphragm having a relatively flexible edge portion and a substantially projecting stiffened portion and a stylus projecting through the wall of said diaphragm adjacent to the tip of said projecting portion and adhesively secured in position by cementing material.

10. The diaphragm for acoustic instruments formed of fabric carrying cementing material, said diaphragm having a relatively flexible edge portion and a substantially projecting conoidal stiffened vibrating portion and a stylus adhesively secured to said diaphragm adjacent the tip of said vibrating portion of the diaphragm.

11. The diaphragm for dictaphone and similar acoustic instruments formed of fibrous material carrying cementing and stiffening material, said diaphragm having a relatively flexible edge portion and a substantially projecting stiffened portion and a stylus secured adjacent the tip of said projecting portion.

HENRY C. EGERTON.
